UNITED STATES PATENT OFFICE.

ISAAC P. RODMAN, OF NEWARK, NEW JERSEY, ASSIGNOR TO GAROD CORPORATION, OF NEWARK, NEW JERSEY, A CORPORATION OF NEW JERSEY.

INSULATOR STRUCTURE FOR ELECTROSTATIC CONDENSERS AND THE LIKE.

Application filed March 8, 1924. Serial No. 697,725.

To all whom it may concern:

Be it known that I, ISAAC P. RODMAN, a citizen of the United States, residing at Newark, in the county of Essex, State of New Jersey, have invented certain new and useful Improvements in Insulator Structures for Electrostatic Condensers and the like; and I do hereby declare the following to be a full, clear, and exact description of the invention, such as will enable others skilled in the art to which it appertains to make and use the same.

This invention has to do with means for effecting improved insulation, and relates, more specifically, to the construction of electrostatic condensers.

The object of this invention is to provide simple and relatively inexpensive means for effecting extraordinarily high insulation and particularly to provide a structure of this kind which may be used to advantage in electrostatic condensers. More specifically, the object of the invention is to provide a variable electrostatic condenser having greatly increased insulation between the two sets of plates and correspondingly greatly reduced losses as compared with the corresponding characteristics of condensers heretofore commonly used.

I have found that in radio practice, and especially radio reception, the losses arising from poor and only moderately good insulation between the fixed and rotatable plates of the variable condensers is a much more important factor than has heretofore been generally recognized. The present invention provides a condenser structure of relatively simple design in which the insulation resistance is exceedingly high and in which the losses due to leakage are practically nil.

The present invention is an improvement on the structure disclosed and claimed in my copending application Serial No. 655,819, filed August 6, 1923. In that copending application the fixed plates are adjustably mounted on rods of dielectric material such as quartz glass, and the arrangement is such that the spacing of the fixed plates with respect to the rotatable plates may be easily adjusted and is further characterized in that the spacing of the plates is substantially un-

disturbed by expansion and contraction of the condenser structure due to temperature variations.

Although the insulation resistance between the fixed and variable plates in the condenser structure described in the above-mentioned copending application is very high, it has been found that a still further improvement could be effected by mounting the supporting rods on pointed set screws or equivalent supporting elements. By this provision the contacts between the dielectric supporting rods and the framework of the condenser structure is reduced to a minimum and the possibility of surface leakage is correspondingly reduced.

One of the most important advantages of this invention arises from the fact that the supporting rods for the fixed plates may be made of a dielectric material of relatively poor insulating qualities as compared, for instance, with that of glass, but which possesses other physical characteristics rendering its use more desirable. For example, it is possible by virtue of this invention to employ supporting rods made of hard rubber or bakelite or other compositions which are a great deal less brittle than glass and yet retain substantially the same high insulation characteristics as could be realized with glass rods in the structure of my copending application. In those cases where the maximum insulation is desired and there is no objection to the sacrifice of physical strength involved, the present invention may be incorporated in a condenser structure in which the supporting rods are made of glass.

The field of usefulness of the improved insulating structure according to this invention is not by any means limited to electrostatic condensers. Insulator structures coming within the scope of this invention may be used to advantage in many cases where it is desired to insure extremely high insulation.

In the accompanying drawing Figs. 1 to 4 inclusive illustrate in plan, elevation and cross section a variable condenser structure in accordance with the preferred embodiment of the invention.

Fig. 1 is a plan view;

Fig. 2 is an elevational view;
 Fig. 3 is a cross-section along the line 3—3 of Fig. 2;

Fig. 4 is a cross-section along the line 5 4—4 of Fig. 3; and

Fig. 5 is a fragmentary cross-section illustrating an alternative arrangement for supporting and centering the rods.

The condenser comprises a group of parallel rotatable plates 1 which are mounted on a shaft 2 and rotatable therewith. A group of parallel fixed plates 3 are each secured together by means of bolts 4 and mounted in proper spaced relation with respect to the 15 rotatable plates 1. The fixed plates are attached by means of three clamping lugs 5 to three supporting rods 6, which may be made of any suitable insulating material such as glass, hard rubber, bakelite, or other 20 dielectric compositions. The two ends of each of the rods 6 are preferably countersunk, as shown in Fig. 4, or counterbored, as shown in Fig. 5, to provide seats for the 25 pointed centering and supporting elements 7 and 8. The element 7 may be a headless pointed set screw, as shown, or any other equivalent device. The element 8 is preferably in the form of a set screw, as shown, and is preferably provided with a lock nut 30 9. The cast frame members 10 and 11 are preferably provided with recesses 10^a and 11^a, into which the supporting rods 6 project. These recesses, as shown in Fig. 4, should be of sufficiently larger diameter than 35 that of the supporting rods so that there is a clearance all around as shown. The counter-sunk recesses in the ends of the rods 6 are preferably of a slightly larger angle than that of the points of the centering elements 40 7 and 8, so that the contacts between the rods and the centering elements is reduced as far as practicable to a mere point contact. Although it is technically preferable that the 45 ends of the supporting rods 6 be countersunk as shown in Fig. 4, it is found that for most purposes the arrangement of Fig. 5, wherein the ends of the rods are counterbored instead of countersunk, is substantially 50 as satisfactory, providing the diameter of the counterbores is relatively small so that the lines of contact between the rods and the supporting elements are short. It is not at all essential to the object sought that the ends of the rods be either countersunk or counterbored. The centering elements 7 and 8 may, for instance, engage the flat end surfaces of the supporting rods if the recesses are not provided. It is obvious 55 that still further equivalent arrangements 60 can be readily devised. The clamping lugs 5 are each provided with a machine screw 12 by means of which the lugs may be caused to grip the supporting rods. When the clamping lugs are loosened, the fixed 65 plate assembly may be moved along the sup-

porting rods for the purpose of adjusting the spacing between the two sets of plates.

The two frame members 10 and 11 are secured together in proper spaced relation by means of three shouldered studs 13 which 70 are provided with cap nuts 14.

The remaining details of the structure illustrated are quite apparent from the drawing, and since they form no part of the present invention, it is thought unnecessary 75 to describe them in detail.

The invention is not limited to variable condensers, as it is equally applicable to fixed condensers of any of the types in which the dielectric between the plates is 80 not of solid form, as, for instance, air and oil condensers. Furthermore, the invention as applied to either a fixed or variable condenser is capable of considerable modification within its spirit and scope. 85

I claim:

1. An electrostatic condenser comprising a plurality of sets of plates disposed in spaced relation one to another, at least one of said sets of plates being supported on a 90 support of dielectric material, and supporting elements in contact with two ends of said support, the contact areas between said supports and said supporting elements being 95 very small.

2. An electrostatic condenser comprising a plurality of sets of plates disposed in spaced relation one to another, at least one of said sets of plates being supported on a 100 rod of dielectric material, supporting elements for engaging the two ends of said rod, the engagement between said rod and said supporting elements being of point contact form.

3. An electrostatic condenser comprising 105 a plurality of sets of plates disposed in spaced relation one to another, a rod of dielectric material, at least one of said sets of plates being supported on said rod, the two ends of said rod being countersunk, pointed supporting elements for engaging the countersunk ends of said rod respectively, said supporting elements being adapted to support said rod.

4. An electrostatic condenser comprising 115 a plurality of sets of plates disposed in spaced relation one to another, a plurality of rods of dielectric material for supporting one of said sets of plates, means for securing said last-mentioned set of plates to said rods, each end of each of said rods being provided with a countersunk recess, and pointed centering elements each engaging through the medium of its point the end of 120 one of said rods, said points being seated in 125 said countersunk recesses.

5. An electrostatic condenser comprising 130 a plurality of sets of plates disposed in spaced relation one to another, a plurality of rods of dielectric material for support-

ing one of said sets of plates, means for clampingly securing said last-mentioned set of plates to said rods, a pair of frame members each having recesses into which the 10
5 ends of said rods project, each end of each of said rods being provided with a conical countersunk recess, and pointed centering

In testimony whereof I affix my signature.

ISAAC P. RODMAN.
